DESIGN FOR A FRUIT JUICE EXTRACTOR

Thomas Raymond Bunton, Calgary, Alberta,
Canada

Application March 11, 1940, Serial No. 90,830

Term of patent 7 years

To all whom it may concern:

Be it known that I, Thomas Raymond Bunton, a citizen of the Dominion of Canada, residing at the city of Calgary, in the Province of Alberta, Canada, have invented a new, original, and ornamental Design for Fruit Juice Extractors, of which the following is a specification, reference being had to the accompanying drawing, forming part thereof.

Fig. 1 is a perspective view of a fruit juice extractor embodying my new design; and

Fig. 2 is a sectional view thereof on the line 2—2 of Fig. 1.

I claim:

The ornamental design for a fruit juice extractor, substantially as shown.

THOMAS RAYMOND BUNTON.
